HYDRAULIC CIRCUIT FOR SAW MILL FEED WORKS

James Roy Stockett, Tulia, Tex.

Application August 29, 1958, Serial No. 758,132

2 Claims. (Cl. 60—51)

This invention pertains to an improved hydraulic circuit for controlling the reciprocating motions of saw mill feed works.

One of the objects of this invention is to provide an improved circuit hookup for the hydraulic actuation of a saw mill feed carriage.

Another object is to provide a hydraulic control circuit for a saw mill feed works which can effect a smooth stopping and starting of the carriage and at the same time provide rapid traverse returning of the carriage at high speed and with great efficiency.

Still another object is to provide a feed, rapid traverse reversing and stop control circuit requiring a minimum of effort and skill on the part of the operator of the saw mill.

It is also an important object of this invention to utilize the initial weight of the massive saw mill carriage to regain a large amount of fluid volume and pressure through a novel check valve arrangement in the circuit when the carriage is stopped at each end of the stroke.

A further object of this invention is to utilize the piston and cylinder of the saw mill carriage as a hydraulic pump as the saw mill carriage is stopped at the end of each stroke so as to pump fluid into an accumulator through a novel check valve arrangement to effect a smooth stopping of the carriage regardless of the manner in which the operator may manipulate the control lever when he moves the lever from the feed position to the stop position, or on over to the reverse position.

And still another object is to provide the above recited hydraulic circuit with critically positioned check valve therein so that the saw mill carriage will stop smoothly against the cushion of air in the accumulator so there will be no sudden jerk or shock when the control lever is manipulated in any manner.

And finally it is the object of this invention to provide a novel hydraulic circuit for a saw mill feed works which utilizes the inertia of the saw mill carriage for recovery of pressure and energy while at the same time effecting a smooth stopping of the carriage at the end of each stroke.

Further features and advantages of this invention will appear from a detailed description of the drawings in which:

The drawing is a diagram showing the hydraulic circuit for a saw mill feed works incorporating the features of this invention.

As an example of one embodiment of this invention there is shown a hydraulic control circuit including a fluid reservoir 10 containing a suitable hydraulic fluid at the fluid level 11. Immersed in the fluid in the reservoir 10 is a control valve 12 having a valve body 13 in which is formed a bore having a series of axially spaced surfaces 14, 15, 16 and 17 separated by annular grooves 18, 19 and 20. A valve spool 21 consists of the axially spaced bearing portions 22, 23 and 24 interconnected by reduced portions 25 and 26 formed integral with the bearing portions 22, 23 and 24. An operating handle 27 is suit-

ably mounted on a supporting pivot pin 28 and is pivotally connected by a pin 29 to the outer end of the stem 30 connected to the valve spool 21 so that by appropriately manipulating the handle 27 the valve spool may be axially reciprocated in the valve body 13.

5 A fluid pressure pump 31 having a suction line 32 receiving a supply of fluid from the reservoir 10 discharges fluid under pressure through the line 33 into the annular groove 19 in the valve body 13, a suitable pressure relief valve 34 being connected through line 35 into line 33 and discharging through line 36 into the reservoir 10 to prevent overloading the pump 31. An air pressure accumulator 37 having an air chamber 38 above the fluid 39 in the bottom portion of the accumulator is connected at its lower end 40 by a line 41 to the annular groove 19 in the valve body 13 so that fluid pressure from the pump 31 through line 33 is always connected to line 41 and the accumulator 37.

15 A fluid pressure cylinder 42 has a piston 43 and a piston rod 44 connected in a suitable manner to a saw mill carriage 45 for reciprocation thereof by controlling the application of fluid pressure in the cylinder 42. One end of cylinder 42 is connected by a line 46 to the annular groove 18 of the valve body 13 while the other end of the cylinder 42 is connected by a line 47 to the annular groove 20 of the valve body 13. Line 46 is connected through a check valve 48 for free flow into line 41 while line 47 is connected through a check valve 49 for free flow into the line 41. Free flow from suction line 50 and check valve 51 into line 46 is provided, while free flow from suction line 52 and check valve 53 into line 47 is also provided, both suction lines 50 and 52 receiving a supply of fluid from the reservoir 10.

25 In operation: When the operating handle 27 is moved to "Stop" position, bearing portion 23 of valve spool 21 closes annular groove 19 so that the pump 31 builds up pressure in the accumulator 37 to the setting of the relief valve 34. At this time the open ends of the bore surfaces 14 and 17 are closed by the respective bearing portions 22 and 24 of the valve spool 21 so as to lock fluid in both ends of the cylinder 42 to bring the carriage 45 to a stop. Check valves 51 and 53 are normally closed at this time and the check valves 48 and 49 are held closed by pressure in line 41.

35 When the operating handle is moved to "Forward" position, annular grooves 18 and 19 are interconnected so that pressure from both the pump 31 and line 41 from the accumulator is applied in line 46 to forwardly actuate the piston 43, check valve 51 being normally closed, and check valve 48 being held closed or floating against pressure in line 41. The other line 47 of the cylinder at this time exhausts out through bore surface 17 back to reservoir 10, check valve 53 being normally closed, and check valve 49 being held closed by pressure from line 41. Thus rapid forward movement is effective for the carriage 45.

45 As the operating handle 27 is returned toward "Stop" position the inertial coast of the heavy carriage 45, causes a suction in line 46 greater than the supply from 50 the annular groove 18 now partially cut off from annular groove 19 but this is automatically relieved by suction through the check valve 51 thus preventing suction spring back as the carriage is brought to a stop. Also, fluid escaping from line 47 of the cylinder under these 55 conditions when restrained from free escape through the bore surface 17 is also relieved by passage through check valve 49 to help again build up pressure in the accumulator 37 for the next return travel of the carriage in reverse direction, check valve 53 being normally closed 60 at this time. Obviously the same operation occurs with the operating handle moved to "Reverse" position and

return, with the appropriate check valves operating as indicated.

By appropriately operating the handle and modulating the position of the valve spool 21 a nicety of smooth and accurate control of the carriage movement can be obtained with accurate, smooth stopping and starting from one reversal to another.

While the apparatus herein disclosed and described constitutes a preferred form of the invention, it is also to be understood that the apparatus is capable of mechanical alteration without departing from the spirit of the invention and that such mechanical arrangement and commercial adaptation as fall within the scope of the appendent claims are intended to be included herein.

Having thus fully set forth and described this invention, what is claimed and desired to be obtained by United States Letters Patent is:

1. In combination in a hydraulic circuit for operating the carriage of a saw mill feed works, a fluid reservoir, a control valve having a valve body, a valve spool reciprocatable in said valve body including means for manually actuating said valve spool, an annular groove in said valve body, a fluid pressure pump receiving a supply of fluid from said reservoir connected to supply fluid under pressure to said annular groove, an accumulator connected to said annular groove, a fluid pressure cylinder having a piston and piston rod connected to actuate said carriage, a second annular groove in said valve body connected to one end of said cylinder, a third annular groove in said valve connected to the other end of said cylinder, a check valve connected between said first men-

tioned annular groove and said second annular groove for free flow between said second annular groove and said first mentioned annular groove, a check valve connected between said first mentioned annular groove and said third annular groove for free flow between said third annular groove and said first mentioned annular groove, a check valve connected between said reservoir and said second annular groove for free flow from said reservoir to said second annular groove, a check valve connected between said reservoir and said third annular groove for free flow from said reservoir to said third annular groove, and means on said valve spool when moved to intermediate stop position to close off said first mentioned annular groove so that said pump is connected solely to said accumulator while said second and third annular grooves are blocked by said valve spool.

2. In a hydraulic circuit as set forth in claim 1 wherein said last mentioned means further includes an arrangement wherein said first mentioned annular groove may be connected to one and the other of said second and third annular grooves while the other of said second and third annular grooves are connected to discharge into said reservoir by the manipulation of said operating handle.
